FOOTREST LIFT ATTACHMENT FOR
CHIROPRACTIC TABLES

Axel V. Fenander, Ladysmith, Wis.

Application February 2, 1950, Serial No. 141,949

3 Claims. (Cl. 311—11)

1

This invention relates to chiropractic tables of the type having a foot rest and a platform at one end, and in particular a toggle attachment for automatically elevating the foot rest of a chiropractic table as the table is lowered to a position suitable for making adjustments.

The purpose of this invention is to provide an attachment that may readily be installed on chiropractic tables which is connected to the table and foot rest thereof in such a manner that the foot rest moves upwardly with the lowering movement of the table.

In the usual chiropractic table it is necessary to raise the foot rest by hand after the table has been lowered and this is objectionable because the patient is inconvenienced thereby. With this thought in mind this invention contemplates pairs of hinged levers connected to the ends of the chiropractic table and to the platform mounting of the table whereby the outward movement of the platform, as the table is lowered elevates the inner ends of the levers whereby with the inner ends of the levers connected to the foot rest the foot rest is automatically elevated.

The object of this invention is, therefore, to provide means for constructing an attachment for chiropractic tables whereby the elements may readily be installed on the table and connected to the foot rest so that the outward movement of the platform raises the foot rest.

Another object of the invention is to provide an attachment for chiropractic tables by which the foot rest is elevated as the table is lowered that may be installed on tables now in use.

A further object of the invention is to provide a foot rest elevating attachment for chiropractic tables which is of a simple and economical construction.

With these and other objects and advantages in view the invention embodies a yoke mounted under the foot rest of a chiropractic table with toggle action levers pivotally connected to a standard at the end of the table and also to an outwardly moving platform of the table whereby with the levers connected to the yoke of the foot rest the foot rest is elevated as the platform moves outwardly.

Other features and advantages of the invention will appear from the following description taken in connection with the drawings wherein:

Figure 1 is a vertical longitudinal section taken on line 1—1 of Figure 2 through the end of a chiropractic table showing the attachment installed thereon.

Figure 2 is a plan view of the end of the table 55 through the rod 35 which is positioned in the

2

taken on line 2—2 of Figure 1 and also illustrating the position of the attachment on the table.

Figure 3 is a side elevational view of the attachment with parts shown in section showing the foot rest in the lower position.

Figure 4 is a cross section through the end of the table showing the foot rest with the yoke of the attachment extended downwardly therefrom 10 and taken on line 4—4 of Figure 1.

Referring now to the drawings wherein like reference characters denote corresponding parts the foot rest toggle attachment of this invention includes a yoke 10 for attaching an outer pair of bars 11 and 12 to the mounting of the standing platform 13, a yoke 14 for attaching vertically positioned bars 15 and 16 to a foot rest 17 and U-clamps 18 and 19 for attaching an inner pair of bars 20 and 21 to a standard 22 of a chiropractic table through arms 23 and tubular rods 24 and 25.

The ends 26 and 27 of the yokes 10 are attached to the hubs 28 and 29 of the platform 13 by set screws 30 and 31, respectively, and the outer base of the yoke is provided with extensions 32 and 33 through which the ends of the bars 11 and 12 are pivotally connected to the yoke by a rod 34.

The opposite ends of the bars 11 and 12 are pivotally connected to the bars 28 and 29 through a rod 35 and, as illustrated in Figure 1 the rod 35 is positioned to register with the slots 36 in vertically disposed bars 37 and 38 that are pivotally connected to downwardly extended ends of the yoke 14 by a rod 39.

The opposite ends of the bars 20 and 21 are pivotally connected through the clamps 18 and 19 to a rod 40 and the clamps are secured on the standard 22 by bolts 41 and 42.

The standard 22 is carried by the outer ends of the arms 23 which are supported in webs 43 of the bars 24 and 25 and the foot rest 17 is provided with downwardly extended rods 44 and 45 that are slidably held in cylindrical sockets 46 and 47 on the outer ends of the rods 24 and 25. The hubs 28 and 29 and the platform 13 are carried by rods 48 and 49 that extend through the bars 24 and 25.

With the parts arranged in this manner the toggle bars extend downwardly, as illustrated in Figure 3 when the chiropractic table is upright and when the table is lowered to the position in which adjustments are made the bars 20 and 21 and 11 and 12 move the foot rest 17 upwardly

notches 36. The upward movement of the foot rest is adjusted by placing the rod 35 in the different pairs of notches.

The attachment may readily be installed on chiropractic tables as disclosed and it will be understood that the attaching elements at the ends of the device may be modified to correspond with tables of different designs.

It will also be understood that other modifications may be made in the design and arrangement of the parts without departing from the spirit of the invention.

What is claimed is:

1. A chiropractic table attachment comprising two pairs of parallel bars, an intermediate rod pivotally connecting the inner ends of the said pairs of parallel bars, a pair of vertically disposed bars having notches in the edges thereof, means pivotally connecting the upper ends of the said vertically disposed bars to a foot rest of the table, means connecting the inner pair of parallel bars to the end of the table, and means connecting the outer pair of parallel bars to an outwardly movable part of the table, said notches of the vertically disposed bars positioned to receive the said intermediate rod connecting the inner ends of the parallel bars. 25

2. A chiropractic table attachment comprising two pairs of parallel bars, an intermediate rod pivotally connecting the inner ends of the said pairs of parallel bars, a pair of vertically disposed bars having notches in the edges thereof, a yoke having downwardly extending ends mounted on a foot rest of the table, a rod pivotally connecting the upper end of the said vertically disposed bars to the downwardly extending ends of the yoke of the foot rest, means connecting the inner pair of parallel bars to the end of the table, and means connecting the outer pair of parallel bars to an outwardly movable part of 40

the table, said notches of the vertically disposed bars positioned to receive the said intermediate rod connecting the inner ends of the parallel bars.

5. 3. A chiropractic table attachment comprising two pairs of parallel bars, an intermediate rod pivotally connecting the inner ends of the said pairs of parallel bars, a pair of vertically disposed bars having notches in the edges thereof, a yoke having downwardly extending ends mounted on a foot rest of the table, a rod pivotally connecting the upper end of the said vertically disposed bars to the downwardly extended ends of the yoke of the foot rest, U-shaped clamps positioned on a standard extended through the end of the table, a rod pivotally connecting the end of the inner pair of parallel bars to the said U-shaped clamps, a yoke mounted on a platform carried by the table, and a rod pivotally connecting the ends of the outer pair of parallel bars to the yoke of the platform, said notches of the vertically disposed bars positioned to receive the said intermediate rod pivotally connecting the inner ends of the pairs of parallel bars. 10 15 20 25
